C. S. HALL

AIRCRAFT

Original Filed March 25, 1924

Charles S. Hall
INVENTOR.

BY *D. Clark*
ATTORNEY.

UNITED STATES PATENT OFFICE.

CHARLES S. HALL, OF LOS ANGELES, CALIFORNIA, ASSIGNOR TO HALL AIRWAYS CORPORATION, OF DOVER, DELAWARE, A CORPORATION.

AIRCRAFT.

Application filed March 25, 1924, Serial No. 701,733. Renewed February 2, 1926.

My invention relates to aircraft of the dirigible type, particularly of the rigid type of construction, and has for its main object to provide a series of compartments having 5 a relatively smooth inner surface wherein may be held a suitable gas containing envelope, or metal container, yet having means of automatically varying the volume of the enclosure so as to equalize the inner pressure with the outer pressure at all altitudes without the necessity of men, known as "riggers," to constantly watch for any undue stresses upon the gas container by reason of the varying sizes and stresses of 15 the gas container at various altitudes.

In the present evolution, a telescoping portion is arranged in conjunction with the gas containing envelope, the said telescoping portion carrying a diaphragm, thus 20 providing a comparatively rigid envelope while the telescoping or collapsing portion will take care of the varying pressures and at the same time this telescoping portion will be comparatively free from entanglements and make possible its upper and downward movement at all times.

Another object is to provide a means of constructing the major portion of the gas containing envelope of non-porous material, such as metal, so that the process of osmosis will be eliminated or reduced to the least possible effects.

Another object is to provide a construction which will avoid, or reduce, as much 35 as possible, the dangers and losses due to osmosis, since it is generally recognized in the art that, with hydrogen as a levitating element, the impurities are generally found at the lower part of the container, while 40 the osmosis takes place more rapidly at the surface of highest pressure, which is, of course, at the top of the container, and thus by making the upper part of non-porous or impervious material, such as metal, or other 45 suitable element, the dangers of explosion of hydrogen due to impurities, occasioned by osmosis, will be reduced or eliminated, or if helium is used, excessive and costly losses will be avoided by the same means. 50 My invention eliminates excessive costs of operation and avoids delays occasioned by necessity or refilling the containers. My invention also reduces the costs of operations due to the reduced lifting capacity of the 55 levitating element.

Having thus described the main objects of my invention I will now describe the same with reference to the accompanying drawings which form an essential part of this specification but which are used for illustration only.

Figure 1 is a side view of the aircraft with the central portion of the outer covering and a portion of the framework removed.

Figure 2 is a cross-sectional view taken on line 2—2 looking in the direction indicated by the arrows thereon.

Figure 3 is a longitudinal section drawn through one of the compartments looking 70 in the direction indicated by the arrows of line 3—3 in Figure 2.

In carrying out my invention as shown and illustrated in the accompanying drawings, in its preferred form, a body, or framework, 1 is provided and an outer covering 2 is arranged thereon. Within the said framework a series of compartments "C" are arranged, the inner surfaces of which are made relatively smooth. Between the 80 said compartment walls the framework 1 is transversely arranged, as can be readily understood. Within the compartment "C" a gas containing envelope 3, made of impervious material, such as metal, is arranged. The lower margin of the said envelope 3 is provided with a framework 4 carrying collapsible element 5 on which diaphragm 6 is arranged.

Now it will be seen that when container 3 is filled with a levitating element under atmospheric pressure the collapsing element 5 carrying diaphragm 6 is close underneath the said framework 4, but as the aircraft ascends, involving a decrease in pressure of 90 the atmosphere entailing a relative increase in the volume of the levitating element in order to maintain equi-static pressures on either side of the diaphragm, the collapsing element 5 automatically varies 100 the position of the said diaphragm, as can be readily understood.

Of course, it is understood that the collapsing element will be made of flexible material, such as rubberized silk, or even of rubber, and that the said container 3 may be connected with other containers by means of tube 7 and valve 8, as shown in Figure 3, through which the air may be discharged or the gas inserted during the filling and operat- 110

ing of the craft. Also by means of a flexible tube 9 and valve 10 the container may be inflated or deflated.

The body or hull 1 is provided with superimposed compartments or chambers. These comprise the upper compartment or chamber 3 previously mentioned, the intermediate compartment or chamber 12, which is provided with windows 13, and a floor 14 on which seats 15 are mounted. Beneath the floor 14 is a lower chamber or compartment 16. These chambers extend longitudinally and transversely of the body as shown.

Having thus described my invention in its preferred form, I claim:

1. In an aircraft having a gas containing element, the combination of; a gas container arranged within a compartment provided in the said aircraft, the said gas container being constructed of impervious material and of a form substantially coinciding with the inner surface of the said compartment; a frame arranged on the said container; and a diaphragm carried on the said frame, the said diaphragm carried by a collapsible element, substantially as described.

2. In an aircraft, the combination of; a body framework; a covering therefor; a series of compartments of relatively smooth inner surfaces arranged in the said body; and a gas container arranged within the said compartment, the said gas container having a collapsible element associated therewith, the said collapsible element having a diaphragm arranged therewith and carried thereon and freely exposed on one side to the atmosphere whereby the collapsible element will automatically vary the position of said diaphragm to equalize the pressures on opposite sides thereof at all altitudes, for the purposes described.

3. In an aircraft, the combination of; a framework; an outer covering arranged on the said framework; a series of compartments arranged within the said framework, the said compartments having relatively smooth inner walls, a gas containing envelope arranged within the said compartment and substantially of the form thereof, the said envelope having a framework associated therewith carrying a collapsible element attached thereto; and a diaphragm carried upon the said collapsible element,

and having its outer face open freely to the atmosphere, whereby pressures are automatically equalized on opposite sides thereof, substantially as disclosed and for the purposes described.

4. In an aircraft, a body frame work forming a series of compartments, gas containing envelopes in said compartments, a plurality of collapsible elements, said collapsible elements being attached to the gas containing envelopes, and a diaphragm attached to each collapsible element, the said compartments having relatively smooth inner walls, within which the gas containing envelopes are encased, said aircraft having an outer covering thereon.

5. In an aircraft, the combination of; a body; compartments arranged within the said body; gas containing envelopes arranged within the said compartments; a collapsible element carried by and in free communication interiorly with the said envelope; and a diaphragm carried by the said collapsible element, said diaphragm being open to the atmosphere on its outer side whereby pressures are automatically equalized on opposite sides thereof, substantially as disclosed.

6. In a gas container for aircraft, the combination of; a collapsible element formed as a continuation of and in freely-open communication with the said container; and a diaphragm carried by the said collapsible element, substantially as disclosed.

7. In a gas container for aircraft, the combination of; an envelope; a collapsible element formed as a continuation of and in freely-open communication with the said envelope; and a diaphragm carried by the said collapsible element, substantially as disclosed.

8. In an aircraft, the combination of a framework, a plurality of longitudinally arranged gas containing envelopes of rigid material enclosed thereby, each having a freely open end, a collapsible chamber secured to and opening into said end, and a diaphragm closing the opposite end of said chamber with its outer side exposed to atmospheric pressure.

In testimony whereof I have signed my name to this specification.

CHARLES S. HALL.
